UNITED STATES PATENT OFFICE.

EDWARD B. HESS AND LEWIS C. MYERS, OF BROOKLYN, NEW YORK, ASSIGNEES TO
ROYAL TYPEWRITER COMPANY, INC., OF NEW YORK, N. Y., A CORPORATION OF
NEW YORK.

TYPEWRITING MACHINE.

1,427,465.

Specification of Letters Patent. Patented Aug. 29, 1922.

Original application filed May 11 1920, Serial No. 380,601. Divided and this application filed June 28, 1920. Serial No. 392,265.

To all whom it may concern:

Be it known that we, EDWARD B. HESS and LEWIS C. MYERS, citizens of the United States of America, and residents of the city 5 of New York, in the borough of Brooklyn, county of Kings, and State of New York, have invented certain new and useful Improvements in Typewriting Machines, of which the following is a specification.

10 The present invention relates generally to typewriting machines and has for its object the production of a spring barrel structure that readily admits of being assembled as a unit before the parts are connected to 15 the machine itself. It consists of the hereinafter described features of construction, a preferred form of which is disclosed in the accompanying drawings in which

20 Fig. 1 is a vertical sectional view of a typewriting machine, the section being in a plane back of the key board, showing the relative location of the spring barrel structure with respect to the shift rail;

25 Fig. 2 is a horizontal sectional plan view of a typewriting machine, with parts omitted and broken away, also for the purpose of showing the location and arrangement of the spring barrel structure with respect to other parts of the machine;

30 Fig. 3 is a detail view of the spring barrel and supporting means therefor looking from the rear of the machine at a point just within the rear framework thereof, that is to say, in the direction of arrow 3 of Fig. 2;

35 Fig. 4 is a vertical sectional view on the line 4—4 of Fig. 5;

Fig. 5 is a sectional view on the irregular line 5—5 of Fig. 3;

40 Fig. 6 is a detail sectional view on the line 6—6 of Fig. 5;

Fig. 7 is a sectional view on the line 7—7 in Fig. 5;

Fig. 8 is a sectional view on the line 8—8 in Fig. 6;

45 Fig. 9 is a sectional view on the line 9—9 in Fig. 5.

This case is a division of application Serial No. 380,601 filed May 11, 1920, in which there is disclosed an improvement on 50 the well known Royal typewriter that consists mainly in a construction in which the transversely travelling carriage indicated at 50 supports a shiftable platen carriage 8, the shiftable carriage being raised and low-

ered by means of shift rail 173 actuated by 55 a suitable system of shift key levers that actuate vertical lifting arms 180. The transversely travelling carriage is mounted on a lower race way 4 suitably supported by the side frames of the machine and connected with the rear wall of the main frame by means of an escapement framing 5 that forms a bridge between the lower race way and the rear wall of the main frame. The shift rail extends transversely of the machine immediately in rear of the lower race way and above a portion of the escapement bridge.

The spring barrel and its supporting means are constructed as follows; a bracket 70 consisting of a connecting portion 265 is provided with two downwardly extending arms 266 and 267, the bracket being secured to the rear wall of the frame by means of screws passing into arm 267. 268 indicates a spring 75 barrel shaft mounted in said arms and having an outboard extension 268^a that projects beyond the arms of the bracket. Mounted loosely at the forward end of said outboard extension is a core 269 to which one end of spring 270 is attached, its other end being secured to the spring barrel in a manner well understood; and said core is provided with a reduced portion 271 having slots 272 for the reception of tongues 273 carried by 80 spring barrel shaft 268^a. In the present instance, said tongues are formed by struck-up portions from a sheet metal head 274 carried on the outer end of said outboard extension so that rotation of the shaft will adjust the 85 position of the core whereby the tension of the spring may be varied in a manner well understood. The adjusting means for the shaft in this instance are located intermediate arms 266 and 267 and consist of an upwardly extending screw 275 mounted in an upwardly extending bushing 276 and engaging with a screw gear 277 carried by sleeve 278 secured to the shaft 268 by screws 279.

Consideration of Figs. 2 and 3 will demonstrate that the adjusting means for the tension of the spring is rendered very accessible being, as a matter of fact, directly beneath the left hand rear dust shed of the casing. Core 269 is provided with an extension 280 for the reception of a ball bearing 281, said bearing being held in place by a lock nut 282 engaging a threaded portion of the exten-

sion 280. 283 is a cup shaped member of sheet-metal constituting with a removable plate 284 a spring barrel. Said cup shaped portion 283 is provided with a neck portion 285 secured to one member of the ball bearings 281, said ball bearing being in effect housed within said neck portion. A spring barrel gear 286 is suitably secured to the spring barrel and engages with the usual 10 pinion-and-ratchet drive mounted on a ribbon feed shaft 287 carried by arm 266 in a manner similar to the construction shown in U. S. Letters Patent No. 859,294. 288 indicates back space-controlling dogs 15 that conveniently find their support on a gland 289 that holds them in position against arm 266. Fig. 2 shows that the spring barrel shaft extends longitudinally of the machine substantially the entire distance between the 20 rear wall of the frame work and the shift rail. In order to admit of the removal of such spring barrel shaft, such shift rail is provided with an oversize hole 290 (see Fig. 1) which is axially co-incident with the 25 spring barrel shaft when the shift rail is in its upper case position. By this means the spring barrel shaft may be withdrawn or inserted through the shift rail. The bracket that supports the spring barrel structure is 30 provided with a bearing 291 in which is hung one arm 292 of a rocking universal frame 19; the other end of said frame being supported by a bracket 293 secured to the rear wall of the frame work and carrying an arm 294 of 35 said universal frame.

The shift key lever system herein disclosed in part is claimed in application Ser. No. 394,672, filed July 8, 1920.

The construction of the shiftable carriage 40 herein disclosed in part is claimed in application Ser. No. 404,534, filed August 19, 1920.

The feature of providing lower raceway 4 with a central gutter is claimed in application Ser. No. 569,322, filed June 19, 1922.

45 We claim:

1. In a typewriting machine: a spring barrel shaft extending longitudinally of the machine, a spring barrel at the forward end of the shaft, a shaft supporting bracket in 50 rear of the spring barrel, and a shift rail extending transversely of the machine in front of the spring barrel and having an opening for removal of said shaft that registers with its axis when the shift rail is in 55 one of its two positions.

2. In a typewriting machine: a bracket having a plurality of bearing arms, a spring barrel shaft mounted in said bearing arms, and having an outboard extension beyond 60 said bearing arms, a core for the spring mounted loosely near the end of the extension, a pin-and-slot connection between the core and shaft at the end of the extension, a barrel mounted loosely with relation to 65 the core and shaft, a spring having its op-

posite ends anchored on the core and barrel, and means intermediate the arms for adjusting the shaft to thereby vary the tension of the spring.

3. In a typewriting machine: a frame having a rear wall, a bracket carried by said rear wall, a spring barrel shaft mounted in said bracket and having an outboard extension beyond said bracket, a core for the spring mounted loosely near the end of the extension, a pin-and-slot connection between the core and shaft at the end of the extension, a barrel mounted loosely with relation to the core and shaft, a spring having its opposite ends anchored on the core and barrel, and means for adjusting the shaft to thereby vary the tension of the spring. 75 80

4. In a typewriting machine: a frame having a rear wall, a bracket carried by said wall, a spring barrel shaft mounted in said bracket and having an outboard extension beyond said bracket, a core for the spring mounted loosely near the end of the extension, a pin-and-slot connection between the core and shaft at the end of the extension, 85 and means, located between the core and the rear wall, for adjusting the shaft and thereby by the core. 90

5. In a typewriting machine: a frame having a rear wall, a bracket carried by said 95 wall, a spring barrel shaft mounted in said bracket and having an outboard extension beyond said bracket, a core for the spring mounted loosely near the end of the extension, a pin-and-slot connection between the core and shaft at the end of the extension, 100 and an upwardly inclined screw carried by the bracket and engaging with the shaft at a point between the rear wall and the outboard extension for adjusting the shaft and thereby the core. 105

6. In a typewriting machine: a main frame having a rear wall, a bracket consisting of a horizontal connecting portion having two dependent arms, one of which is 110 connected to the rear wall, and a bushing extending upwardly from said connecting portion, a spring barrel shaft mounted in said dependent arms and having an outboard extension projecting beyond the 115 bracket, a core for the spring mounted loosely near the end of the extension, connecting means at the end of the extension between the shaft and the core, and an adjusting screw for the shaft mounted in the 120 bushing. 125

7. In a typewriting machine: a main frame having a rear wall, a bracket consisting of a horizontal connecting portion having two dependent arms, one of which is 125 connected to the rear wall, a bushing extending upwardly from said connecting portion; a spring barrel shaft mounted in said dependent arms, an adjusting screw for the shaft mounted in the bushing, and a uni- 130

versal bar bearing carried by the connecting portion.

8. In a typewriting machine: a bracket, a spring barrel shaft carried thereby and having an outboard extension, projecting beyond the bracket, provided with a sheet metal head having inwardly pressed lugs, a core for the spring loosely mounted on said shaft, having slots for the reception of said lugs, and means for adjusting the shaft and thereby the core.

9. In a typewriting machine: a main frame having a rear wall, a spring barrel bracket connected to said wall, spring barrel mechanism carried by said bracket, a second bracket connected with the rear wall, and a universal bar mounted in the two brackets.

10. In a typewriting machine: a main frame having a rear wall, a spring barrel bracket connected to said wall, a spring barrel shaft mounted in said bracket and extending longitudinally of the machine, a second bracket connected with the rear wall,

and a universal bar extending transversely 25 of the machine beneath the spring barrel shaft and mounted in the two brackets.

11. In a typewriting machine: a bracket, a spring barrel shaft mounted in said bracket and having an outboard extension 30 projecting beyond said bracket, a core for the spring mounted near the end of said extension and having an inwardly projecting sleeve, connections between the core and shaft at the outer end of the extension, a ball 35 bearing mounted on said sleeve, a barrel rotating on said ball bearing, binding means associated with said core and sleeve to prevent endwise displacement of the ball bearing, a gland surrounding the shaft between 40 the bracket and the binding means, and back-shift controlling means on said gland and adjacent the bracket.

Signed at New York city, in the borough of Manhattan, county and State of New 45 York, this 23rd day of June, 1920.

EDWARD B. HESS.
LEWIS C. MYERS.
